UNITED STATES PATENT OFFICE.

FRED C. LEACH, OF MARION, OHIO.

DESIGN FOR A MEMBER FOR COLLAR-BUTTON NECKTIE-FASTENERS.

SPECIFICATION forming part of Design No. 31,304, dated August 1, 1899.

Application filed June 15, 1899. Serial No. 720,703. Term of patent 14 years.

To all whom it may concern:

Be it known that I, FRED C. LEACH, a citizen of the United States, residing at Marion, in the county of Marion and State of Ohio, have invented new and useful Improvements 5 in a Design for a Member of a Collar-Button Necktie-Fastener, of which the following is a specification.

My invention relates to a design for a member of a collar-button necktie-fastener, as illustrated in the accompanying drawings, in which—

Figure 1 is a rear perspective view. Fig. 2 is a front perspective view. Fig. 3 is a side 15 elevation.

My design consists of a slotted stem *a*, hav-

ing a U-shaped member *b*, the outer face of which is provided with two downwardly-extending arms *c*.

Having thus described my invention, what 20 I claim, and desire to secure by Letters Patent, is—

The design for a member of a collar-button necktie-fastener, substantially as herein shown and described.

In testimony whereof I have hereunto set my hand in the presence of two subscribing witnesses.

FRED C. LEACH.
